UNITED STATES PATENT OFFICE.

SOL BROWN, OF NEW ORLEANS, LOUISIANA.

DESIGN FOR A SIRUP PITCHER.

Application filed November 13, 1922. Serial No. 4,271. Term of patent 14 years.

To all whom it may concern:

Be it known that I, SOL BROWN, a citizen of the United States, residing at New Orleans, in the parish of Orleans and State of Louisiana, have invented a new, original, and ornamental Design for a Sirup Pitcher, of which the following is a specification, reference being had to the accompanying drawing, forming a part thereof.

On the drawing:

The figure is a perspective view of a sirup pitcher showing my new design.

I claim:

The ornamental design for a sirup pitcher as shown.

SOL BROWN.
